UNITED STATES PATENT OFFICE.

JOHN F. BOYN, OF NEW YORK, N. Y.

NOZZLE FOR PNEUMATIC CLEANERS.

1,106,695.

Specification of Letters Patent. Patented Aug. 11, 1914.

Application filed October 3, 1912. Serial No. 723,697.

To all whom it may concern:

Be it known that I, JOHN F. BOYN, a citizen of the United States, and a resident of New York, borough of Brooklyn, county of 5 Kings, and State of New York, have invented a certain new and useful Improvement in Nozzles for Pneumatic Cleaners, of which the following is a full, clear, and exact specification.

10 This invention relates to a class of devices adapted to be used in conjunction with pneumatic cleaners.

My invention has for its object primarily to provide a form of nozzle designed to be 15 employed especially upon the end of the tube of a pneumatic cleaner into which is admitted the dust, or refuse from the article being cleaned, and wherein is provided a yieldingly movable broom which is adapted 20 to penetrate between the strands of the fiber, or nap of the article when the cleaner is guided over its surface, thereby agitating the dust settled therein so that the suctional action of the currents of air may effectually 25 remove all the particles.

A further object of the invention is to provide a nozzle of compact and efficient construction, and which may be made in any desired shape so as to be adapted for use in 30 conjunction with pneumatic cleaners of various types.

A practical embodiment of the invention is represented in the accompanying drawing forming a part of this specification in which 35 similar characters of reference indicate corresponding parts in all the views, the said invention being more fully described herein-after, and then pointed out in the appended claims.

40 In the drawings, Figure 1 is a perspective view of one form of nozzle embodying my invention. Fig. 2 is a side elevation, partly sectional and partly broken away, of the device. Fig. 3 is a section taken on the line 45 II-II of Fig. 2. Fig. 4 is a fragmentary side view of one end of the broom. Fig. 5 is a fragmentary inverted plan of one end of the back of the broom, and Fig. 6 is an end view of the broom.

50 The nozzle, or device comprises a chambered head, or casing 10 which is preferably substantially rectangular in form whereby end walls 11 and 12 are provided, though said chambered head may be of any desired 55 shape. The head 10 may be formed with a

curved top, as 13, and an open under side so as to provide a mouth, as 14. Projecting preferably upon an incline from the curved top 13 of the head is a tubular neck, or pipe 15 the passage through which communicates 60 with the chamber interiorly of said head, and this neck serves to permit the nozzle to be applied upon the tube, as 16, of the usual, or any preferred form of pneumatic cleaner.

To each of the end walls 11 and 12 of the 65 chambered head 10 are two vertically disposed guide strips, or plates 17, and 18, and the pairs of said plates extend interiorly of the head in opposed aligned arrangement. Each pair of the plates 17, and 18 are spaced 70 apart, as shown, whereby grooves 19 are provided therebetween, and in said grooves is a movable broom 20 which serves to agitate the dust, or refuse which may be settled between the fiber, or nap of a carpet, or rug, 75 or other similar article of woven fabric when the nozzle is being guided thereover.

The broom 20 has a back, 21, composed of an elongated plate of metal which is bent through its longitudinal center and reflexively 80 disposed relatively to each other, whereby the bristles may be secured between the opposing edge portions thereof, and said back is of sufficient length so that its ends are slidably disposed in the groove 19 between the plates 85 17 and 18. Between the opposed edge portions of the back 21 are clamped or fastened the ends of the strands of one or more rows of bristles 22 of fine pieces of wire, or other 90 stiff flexible material.

Serving to permit the broom 20 to be yieldingly movable in the chamber head 10 of the nozzle, upon the top of the back 21 thereof is secured the central part of a spring 23. The end portions of the spring 95 23 are curved upwardly so as to contact with the underneath surface of the top 13 of the head, thereby permitting said spring to normally force the broom down upon the surface to be cleaned.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

100

105

110

Having thus described my invention, I claim as new and desire to secure by Letters Patent:-

1. In a nozzle for pneumatic cleaners, the combination of a housing substantially arch-shaped in cross section and having closed ends, a plate fixed upon the inner surface of each of the end walls and provided with a vertical groove, a brush having its ends slidably held in said grooves, said brush having a spring secured to the back thereof, and yieldingly engaging the top of the housing, whereby the brush is yieldingly held in said grooves.
- 10 2. In a nozzle for pneumatic cleaners, the combination of a substantially arch-shaped housing having side walls and end walls and

an open bottom and provided with an air outlet, each of said side walls having a vertically disposed groove on the interior surface thereof, a removable brush disposed longitudinally within the housing, and having its ends disposed within the said grooves, whereby the brush is slidably held within the grooves, a leaf spring provided between the brush and the top of said housing, and secured to the brush whereby a yielding pressure is exerted upon the brush.

This specification signed and witnessed this second day of October, A. D. 1912.

JOHN F. BOYN.
